UNITED STATES PATENT OFFICE.

ADOLPH LEHMANN, OF HICKSVILLE, NEW YORK, ASSIGNOR TO MABEL CHRIST, OF HICKSVILLE, NEW YORK.

ROPE-CLAMP.

1,259,881.

Specification of Letters Patent.

Patented Mar. 19, 1918.

Application filed March 16, 1917. Serial No. 155,166.

To all whom it may concern:

Be it known that I, ADOLPH LEHMANN, a subject of the Emperor of Germany, and resident of Hicksville, county of Nassau, 5 State of New York, have invented certain new and useful Improvements in Rope-Clamps, of which the following is a specification.

The device the subject of this invention is 10 intended to be used as a means for securing together the broken ends of a rope or for securing two portions of rope to form a continuous unit.

My device has for its particular objects 15 and advantages the construction of a member usually formed of metal and which shall be quick and simple in operation, and simple in construction so that it will not get out of order.

20 Further, certain of the parts are quite automatic in operation and because of the automatic features the device may be attached or released with great rapidity.

The construction and operation of my device will be fully set forth as the specification progresses.

The following is what I consider a good means of carrying out this invention and the accompanying drawings should be referred to for a complete understanding of the specification which follows:—

In the drawings:—

Figure 1 is a side elevation of a completed device.

35 Fig. 2 is a plan view thereof.

Fig. 3 is a plan view of one of the jaws.

Fig. 4 is an end elevation of a complete clamp member.

40 Fig. 5 is a sectional view of one of the jaws.

Fig. 6 shows in elevation a spring.

Fig. 7 is a sectional view of one of the jaws and the spring therein. This figure is taken on the line 7—7 of Fig. 3.

45 Similar reference numerals indicate like parts in all of the figures where they appear.

What I may term as the body portion of my device may be constructed of any suitable material such as cast steel, malleable iron, or copper or bronze. This body portion is somewhat oval in shape being of a great width at the center as shown at 1 and reduced at each of its ends 2 and 3.

50 At each reduced end I provide a strength- 55 ening flange 4 and 5 which flanges should

be annular, and in the body member I produce apertures or openings extending quite through the body as shown at 6.

Within the body I recess out a portion of the material approximately on the lines 7 60 and 8 so that other members to be later described may be readily inserted or removed and at each end of the body member I provide tapered openings extending outward on the lines 9 and 10.

65 Fitted in each of the tapers 9 and 10 are clamps comprising opposed members 11 and 12 and 13 and 14. These members are also tapered at an angle co-incident to the tapers 9 and 10 and within recesses in the 70 clamping members, I arrange springs 15 and 16 and 17 and 18.

75 The springs 15 and 16 are secured in the jaws 11 and 12 and the springs 17 and 18 are secured in the jaws 13 and 14, and as shown in Fig. 3, the springs are received in recesses in the jaws with which they operate and tend to open the jaws or spread them away from each other.

80 When the jaws are in operable position the position in which the jaws 11 and 12 are shown the tapered portion of the body member closes the jaws together, but when the jaws are moved inward as are 13 and 14 the springs open the jaws away from each other 85 and in this position a rope may be readily inserted.

85 Should it be desired that the jaws be removed it is only necessary to move them to the position shown by 13 and 14 and then by 90 removing the springs 17 and 18 the jaws may be withdrawn. The taper of the parts prevents a removal of the jaws outward through their tapered passages, and as the jaws are each provided with a collar or enlargement 95 21, 22 and 23, the springs will cause these enlargements to engage the body member and will prevent the removal of the jaws until the springs are removed. Thus it will be seen that the jaws or clamps cannot accidentally be displaced or lost.

100 In forming the jaws I have constructed them so that they will positively engage a rope inserted between them. To accomplish this I provide each jaw with a V-shaped 105 trough 24 and 25 extending the full length of the jaw and I may roughen the interior of each V shaped trough as shown at 26. It will however be understood that although at 26 I have shown longitudinal teeth or pro- 110

jections any series of corrugations or serrations may be employed.

At 27 and 28 I indicate that certain portions of the clamping members are reduced.

5 This is merely for the purpose of reducing the frictional area of the clamping members although I may introduce a lubricant such as grease into these reduced portions.

It will be noted that the springs are introduced into annular grooves turned in the jaw members, and that these grooves are of sufficient depth to retain the springs away from the rope engaging portions of the jaws. The 10 grooves are, however, open and when a rope 15 is removed the springs may be withdrawn or removed through their respective grooves.

It will also be noted that the free ends of each spring are turned inward to a very slight degree so as to prevent the springs 20 catching on their co-incidental grooves.

Modifications may be made within the scope of the appended claims without departing from the principle or sacrificing the 25 advantages of this invention. Any of the proportions of my device may be changed, as the device will be constructed to provide for the strength required for a given size of rope.

Having carefully and fully described my invention what I claim and desire to secure 30 by Letters Patent is:

1. A rope clamp comprising a hollow body

member having a tapered opening at each end thereof, relatively tapered jaws at each end of said body member and a spring secured within said jaws for urging them away 35 from each other.

2. A rope clamp having a body member of generally oval shape and a central aperture therethrough, tapered apertures one at each end of said body member and relatively 40 tapered clamps in said tapered apertures and closed by an outward movement.

3. A rope clamp having a generally oval shaped body member provided with a centrally disposed aperture, tapered apertures 45 extending longitudinally of said body member and at the ends thereof, correspondingly tapered clamping members in said body member and adapted to be closed by a relative movement in said body member, each 50 said clamping member being provided with a spring for urging the jaws of each said clamping member away from each other all combined for joint operation as and for the purpose set forth.

55 Signed at New York city, in the county and State of New York, this 13th day of March, 1917.

ADOLPH LEHMANN.
